UNITED STATES PATENT OFFICE.

THOMAS GREGG, OF LARNE, IRELAND.

TAR HEATING AND SPRAYING APPARATUS COMBINED WITH STEAM ROAD ROLLERS.

Application filed October 1, 1927, Serial No. 223,420, and in Great Britain February 23, 1927.

This invention relates to improvements to apparatus used in combination with steam road rollers for heating tar or the like and for distributing the same for road making purposes.

According to this invention, a tar tank is located across the smoke box of the steam road roller and preferably partly within the said smoke box so that the hot flue gases of the steam roller may be used to heat the tar. The tar tank may be provided with a jacket around it through which the hot flue gases pass.

In conjunction with the tar tank, means may be provided for distributing tar from the tank on to the road surface to be treated.

Other features of the invention will appear from the following description and will be pointed out in the claims appended.

The invention will now be described by way of example with reference to the accompanying drawings whereon:—

Fig. 1 is an elevation of a steam road roller having the tar heating tank combined therewith in accordance with the invention.

Fig. 2 is a plan view corresponding to Fig. 1.

Fig. 3 is a cross sectional elevation through the tar tank.

Fig. 4 is a view of a tar tank showing a modification.

Referring to the drawings:—

In the example shown at Figs. 1 and 2 a steam road roller 1 is shown with a tar heating tank 2 located transversely across, and partly through the smoke box 1^a of the steam road roller. The tank 2 is shown jacketed, by flues 2^a leading the hot gases from the boiler smoke box 1^a to the chimney 1^b of the steam road roller 1.

The tar tank 2 lies across the smoke box with a portion 2^b of the bottom of the tank 2 and portions of the front and back of the tank within the smoke box and exposed directly to the hot gases in the smoke box 1^a, the remainder of the tank 2 being heated by the waste heat from the smoke box passing around the flues 2^a which form an enclosing jacket for the remainder of the tank surface.

By this arrangement the tar tank 2 is heated, or the heating of the tar tank is supplemented by the hot gases in the jacketing flues 2^a which give a simple, economical and effective heating means.

The flues 2^a which form the heating jacket pass to the chimney 1^b. A bye-pass flue 3

(Figs. 1, 2 and 3), is provided through the tank 2 for the purpose of passing the waste gases from the smoke box 1^a directly to the chimney without passing round the jacket 60 flues 2^a of the tank 2, a control valve or damper 3^a closing and opening the bye-pass flue 3 when required.

In addition to the waste heat for heating the tank as described, I provide (see Fig. 2) 65 heating means such as a steam coil 5 in the tank itself, live steam being supplied to this heating coil 5, from the boiler of the road roller and under suitable control.

Distribution of the tar or the like from the 70 tar tank 2 is obtained by means of a pump 6 and a transverse distributing pipe 7 provided with spraying nozzles. The pump 6 is driven by chain gearing from the crank shaft 1^c of the steam road roller 1. This pump 6 is 75 also adapted to be used for filling up the tar tank 2 from a tar boiler or other receptacle brought to a convenient position near the steam road roller. Suitable pipes 8 and 8^a and connections from the pump 6 with the 80 necessary valves 9 and 9^a are provided to permit of shutting off the connection between the pump 6 and the spraying pipe 7 when the tank is being filled. The filling connection 8^a to the pump 6 is capable of being 85 closed by the valve 9^a when the pump 6 is being used for spraying the tar from the tank.

A rotary pump 6 is shown, but any other suitable pump, and any other suitable distribution and filling arrangement may be used as 90 desired.

In the modification shown in Fig. 4, pipes or passages 4 are formed as flues through the tank from the smoke box so as to heat the tar effectively. The tank 2 is shown saddled 95 on the smoke box.

It will be understood that various constructional modifications of the apparatus are possible.

I claim:—

1. The combination with a steam road roller of means for heating tar comprising a tank for tar located across, and partly within, the smoke box of the steam road roller, and a jacket around said tank through which jacket hot flue gases from heating the boiler of the roller pass to heat the tar in said tank.

2. The combination with a steam road roller of means for heating tar comprising a tank for tar located across the smoke box of the steam road roller, a jacket around

said tank through which jacket hot flue gases from heating the boiler of the roller pass to heat the tar in said tank, and a steam coil in said tank leading from the 5 boiler of the roller to heat the tar further by means of live steam.

3. The combination with a steam road roller of means for heating tar comprising a tank for tar located across, and partly within, the smoke box of the steam road roller, a jacket around said tank through which jacket hot flue gases from heating the boiler of the roller pass to heat the tar in said tank, and a steam coil in said tank leading from the 10 boiler of the roller to heat the tar further by means of live steam.

4. The combination with a steam road roller of means for heating tar comprising a tank for tar located across the smoke box 20 of the steam road roller, a jacket around said tank through which jacket hot flue gases from heating the boiler of the roller pass to heat the tar in said tank and a damper controlled flue passing through said tank to regulate the heating of the tar by controlling the passage of hot flue gases.

5. The combination with a steam road roller of a tank for tar located across, and partly within, the smoke box of the steam road 30 roller, a jacket around said tank through which jacket hot flue gases pass to heat the tar in said tank, flues passing through said tank for the passage of hot flue gases, and a steam coil in said tank leading from the 35 boiler of the roller to heat the tar further by means of live steam.

6. The combination with a steam road roller of means for heating tar comprising a tank for tar located across the smoke box 40 of the steam road roller, a jacket around said tank through which jacket hot flue gases from heating the boiler of the roller pass to heat the tar in said tank, and means for spraying the tar from the tank on to a road.

45 7. The combination with a steam road roller of means for heating tar comprising a tank for tar located across, and partly within, the smoke box of the steam road roller, a jacket around said tank through which 50 jacket hot flue gases from heating the boiler of the roller pass to heat the tar in said

tank, a steam coil in said tank leading from the boiler of the roller to heat the tar further by means of live steam, and means for spraying tar from the tank on to a road.

55

8. The combination with a steam road roller of means for heating tar comprising a tank for tar located across, and partly within, the smoke box of the steam road roller, a jacket around said tank through which 60 jacket hot flue gases from heating the boiler of the roller pass to heat the tar in said tank, flues passing through said tank for the passage of hot flue gases, a steam coil in said tank leading from the boiler of the roller 65 to heat the tar further by means of live steam, and means for spraying tar from the tank on to a road.

9. The combination with a steam road roller of means for heating tar comprising a tank for tar located across, and partly within, the smoke box of the steam road roller, a jacket around said tank through which 70 jacket hot flue gases from heating the boiler of the roller pass to heat the tar in said tank, 75 flues passing through said tank for the passage of hot flue gases, a steam coil in said tank leading from the boiler of the roller to heat the tar further by means of live steam, a power driven pump adapted to draw 80 tar from the tank and a spray through which said pump delivers tar on to a road.

10. The combination with a steam road roller of means for heating tar comprising a tank for tar located across, and partly within, the smoke box of the steam road roller, a jacket around said tank through which jacket hot flue gases from heating the 85 boiler of the roller pass to heat the tar in said tank, a damper controlled flue passing 90 through said tank to regulate the heating of the tar by controlling the passage of hot flue gases, a steam coil in said tank leading from the boiler of the roller to heat the tar further by means of live steam, a power 95 driven pump adapted to draw tar from the tank, a spray through which said pump delivers tar on to a road, and means whereby the pump can be used to fill the tank from an external tar container.

100

In testimony whereof I affix my signature.
THOMAS GREGG.
